COMBINED TYPEWRITING AND COMPUTING MACHINE

Otto Thieme, Hartford, Conn., assignor to Elliott-Fisher Company, New York, N. Y., a corporation of Delaware

Original application June 18, 1928, Serial No. 286,218. Divided and this application October 12, 1931, Serial No. 568,315

6 Claims. (Cl. 235—59)

This invention relates to combined typewriting and computing machines in which the numeral-keys of the typewriter drive a master wheel, the latter being employed to rotate the dial-wheels of a totalizer.

Each dial-wheel usually has a carry-over mechanism for operating the dial of next higher denomination. Sometimes the active train of dials and carry-overs is very long, and the resistance of so many parts reacts upon the master wheel, which may therefore be caused to fall a trifle short of executing its full stroke. This may cause faulty operations of other parts of the delicate adding mechanism, and may sometimes bring about a mistake in the calculation.

The object of this invention is to overcome this difficulty. To this end, each of the nine cams which index the master wheel and also drive it, is given a form to impart an excessive throw to the master wheel. This extra throw gives the result that the movement proceeds through a long train of dials and carry-overs with sufficient reliability to ensure that the final wheel in the train is properly operated. Upon the return stroke of the key, the master wheel stands idle, being unclutched from the key.

It results that at every numeral-key stroke, the master wheel is rotated a little too far at one stage. This excess happens at a point when the type has made about three-quarters or four-fifths of its travel to the platen of the typewriter.

The cam is further shaped to cause the master wheel to recoil from its overthrown position, or to bring back the master wheel accurately to a perfect position, before the type reaches the paper.

The original extra throw which is imparted to the master wheel and to the train of dials and carry-overs, is therefore an intermediate operation, and is corrected by the key during the remainder of its down stroke, so that the desired extra impulse or extra throw is given to the train without bringing it to a false position at the conclusion.

The cam therefore has a form to give the master wheel an excessive stroke and continues with a further form to restore the master wheel to its exact desired position, at the conclusion of the printing stroke of the type-key.

Still other features are to insure the carrying over of each digit-wheel by mechanically overthrowing the normal carry-over position, then retracting to the true carry-over position, and thus compensating for the slack and resistance in a long one-way driving train that otherwise

might incompletely carry over to the wheel of next higher denominational order.

This application is a division of my pending application No. 286,218, filed June 18, 1928.

Other features and advantages will hereinafter appear.

In the accompanying drawings,

Figure 1 is a vertical section through an Underwood typewriting machine, showing a totalizer mounted upon a truck movable with the typewriter-carriage, a totalizer-actuating mechanism at the front of the machine-frame with the associated typewriter parts connected thereto.

Figure 2 is an enlarged detail operational view, showing the overthrowing action of an actuating sector upon its crank-arm to compensate for slack in a long series of carry-over mechanisms.

Figure 3 is an enlarged vertical section through the totalizer, and a diagrammatic assembly of the operative train of mechanisms between the totalizer and a fully depressed numeral-key.

Figure 4 is an enlarged front view of the master-gear clutch-operating connections.

Figure 5 is an enlarged view, partly in section, showing the relative assembly of the master-gear and its driving clutch-members upon the shaft, as for a stock-unit.

The Underwood typewriting machine includes alphabet-keys 30 and numeral-keys 31, which, when depressed, operate key-levers 32 extending rearwardly to fulcrum upon a pivot-wire 33 to vibrate a bell-crank 34 swingable about a fulcrum-wire 35, to vibrate a type-bar 36 radially swingable about a curved fulcrum-wire 37, to strike the front face of a platen 38 mounted to rotate within a platen-frame 39, case-shiftable within a carriage 40 movable upon a carriage-guiding rod 41, and further provided with a center roll 42 to run upon a track 43 at the front of the machine-frame 44. The carriage 40 has a feed-rack 45 in train with a pinion 46 that drives an escapement-wheel 47 operative through a carriage-motor, not shown, to effect letter-spacing movements of the carriage by escapement-dogs 48 vibrated by a universal bar 49 driven rearwardly through the impact of each type-bar in typing.

The computing mechanism may be divided into two mechanisms, an actuator-mechanism 67, fixed to the machine-frames, and a totalizer-mechanism 68 movable with the carriage 40. The frame preferably is cast with a rail-section 71 along the upper edge, through which a

V-shaped groove 72 is machined to provide bearing faces for rolls 73.

A rail 79, having an inverted V-shaped race-way to ride upon the rolls 73, is driven to and fro by connections with a pair of arms 80, one arm secured at each end of the front rail 81 of the carriage-frame 40 by screws 82, Figure 1.

The rail 79 has permanently secured to the front face thereof a truck 103 for carrying a series of totalizers. Each totalizer may be adjustably secured to establish a computing zone in passing through a stationary actuating mechanism.

Upon shaft 138 there are mounted a series of camming actuators 139, one actuator for each numeral-key.

Each actuator has pivoted at the side thereof, as at 148, a sheet-metal link 149 pendent therefrom with the lower end 150 extending below the plane of the keys, and each link is connected to a key-lever through a pin-and-slot connection 160.

The actuator-cams 139 are alike in size and shape, but the scope of the camming slots 212 varies with each actuator to enable each actuator, when vibrated by its numeral-key, to convey a rocking motion to a universal shaft 213, equivalent to the numerical value of the key depressed; hence the uniform depression of all the numeral-keys uniformly vibrates their actuators 139 a fixed extent, but the variations in the slots 212 convey differential rocking motions to the shaft 213 through each slot engaging a stud 214 carried by crank-arms 215 individual to each actuator and permanently mounted upon the shaft 213 in a straight uniform plane.

The shaft 213 and its series of crank-arms 215 are at the driving end of a connected train of mechanisms operative to positively accomplish a definite result at the driven end of the train, while the actuator-cams are at the end of a driven train actuated by the numeral-keys.

Secured to the shaft 213 is a crank-arm 221. The free end of the arm 221 has a stud 223 projecting from the face thereof, upon which the lower end of a link 224 is mounted, and the upper end of said link is pivotally secured to a gear-sector 225, which in turn is connected to a pinion 242. The depression of a numeral-key 50 moves its link 149 and sector 139 to operate a clutch-mechanism to connect the pinion 242 to the master gear 246 during the printing stroke of the key.

The pinion 242 is the driven element for a train of parts that rotate the master-gear 246, see Figure 5, and are all supported upon a shaft 247 secured to said master-gear, and which rotates within bearings in two brackets (not shown). The pinion 242 is formed integrally with a clutch-member 249 having an even number of slots 250 through the periphery thereof. The pinion 242 and its clutch-member 249 are spaced apart and rotate freely as a unit upon the shaft 247 between a collar 251 and a sleeve 252 flush with the end of the shaft 247. To co-operate with the clutch-member 249 there is mounted on the shaft 247 a clutch-member 253 slidable along said shaft and having a head 254 formed with suitable clutching teeth 254 to interlock within the slots 250 of the clutch-member 249, a second head 255 having diametrically disposed tongues 256 to slidably engage within the slots 257 cut through a head 258 forming a part of the master-gear 246. The assembly 75 of these parts, as shown at Figure 5, provides

that the clutch-head 253 may be shifted leftward to force the teeth 254 into clutching interlock with the slots 250 of the member 249, but the tongues 256 are not withdrawn from the slots 257 of the master-gear.

It will be noted at Figures 4 and 5 that an annular groove 259 separates the two heads 253 and 255 of the sliding clutch-member, and within this groove 259 a roll 260, pivotally mounted upon the rear face of a crank-arm 261, operates to shift the clutch-member along the shaft 247. The arm 261 may be mounted upon a stud 262 secured to the actuator-frame, and said arm may include a second arm 263 carrying a stud 264 having a groove that rests within the forks 265 of a yoke 266 pivotally straddling the end of a lever 267 secured to a rock-shaft 268 having end bearings in the sides of the frame.

The rock-shaft 268 is vibrated by the initial down stroke of each cam-actuator 139 to close the master-gear driving clutch before motion is transmitted to the gear-sector 225.

The return swing of a cam-actuator 139 will reversely rock the shaft 268 idly and permit the springs 287 and 288 to restore the connections 100 that vibrate the clutch-member of the master-gear.

The totalizer-mechanism includes numeral-wheels 303, see Figure 3, idler gears 304, carrying gears 301, star-wheels 305, and carry-over 105 pinions 306.

In a totalizer-mechanism having a long series of numeral-wheels the subtraction of a small number from a series of "0" reverses the carry-over movements of the digits to exhibit a long 110 line of "9" at the left of the number computed. The simultaneous reverse carrying from "0" to "9" on so many numeral-wheels indicates a certain resistance the depressed key must overcome, and this extra driving strain placed upon 115 the connections between the key-lever and the master-gear makes it possible that the full depression of a key will not fully rotate the master gear, and the driven numeral-wheel may not be fully rotated to its true register-aligning 120 position.

To prevent such operating conditions, the camming slot 212 in each actuator 139 is formed with an overthrowing extension as 338, to overthrow the master gear 246 and then restore 125 said gear to its correct wheel-arresting position. In this manner the master gear, which has an excess of rotary motion and which is subsequently withdrawn before the key is fully depressed, insures a true digital movement of 130 the actuated numeral-wheel regardless of any retarding influence of the driven parts.

This overthrowing or overfeeding extension 338 in the slot 212 of the actuator 139 is indicated at Figure 2 where the stud 214 has completed the overthrow of the master gear 246 and rests upon the highest point of the extension 338 and is about to drop therefrom to a dwell 334 of the slot 212, which drop reverses the direction of rotation for the overfed master gear back to a fixed stop-position until released by the release of the depressed key. The initial restoring movement of the actuator-extension 338 vibrates the stud 214 and its connections in two directions, but these are idle motions 140 because the master gear 246 has been cut off by the opening of the clutch to the driving mechanisms.

The actuators 139 have slots 212, and each slot has an overthrowing formation 338, which 150

overthrowing feature on a single actuator of any denomination will be found sufficient to reduce satisfactorily any spirality in the usual commercial totalizer, which is limited to seven denominations.

Variations may be resorted to within the scope of the invention, and portions of the improvements may be used without others.

Having thus described my invention, I claim:

- 10 1. In a typewriting machine having numeral typing keys, the combination with a computing mechanism including numeral-wheels having carry-over connections, one to the other, and a master-gear for driving the numeral-wheels, of means actuated by the numeral-keys and operatively connected to drive and overthrow the master-gear and a numeral-wheel, to insure a complete carry-over, and then restore the same to correct position. 80
- 15 2. In a typewriting machine having numeral typing keys, the combination with a computing mechanism including numeral-wheels having carry-over connections, one to the other, and a master-gear for driving the numeral-wheels, of camming means actuated by the numeral-keys and operatively connected to drive and overthrow the master-gear and a numeral-wheel, to insure a complete carry-over, and then restore the same to correct position. 85
- 20 3. In a combined typewriting and computing machine having numeral-type-keys, a carriage, a totalizer having carry-over trains, and a master-wheel engageable in denominational order with said totalizer by means of said carriage, the combination of a key-operated indexing cam for driving said master-wheel, said cam being formed to impart an excessive throw to the master-wheel and then retract the latter to correct position, and means to disconnect the master-wheel, while in said correct position, from the cam at the conclusion of the printing stroke of the key. 90
- 25 4. In a combined typewriting and computing machine having numeral-type-keys, a carriage, a totalizer having carry-over trains, and a master-wheel engageable in denominational order with said totalizer by means of said carriage, the combination of a key-operated indexing cam for driving said master-wheel, said cam being formed to impart an excessive throw to the master-wheel and then retract the latter to correct position, and means to disconnect the master-wheel, while in said correct position, from the cam at the conclusion of the printing stroke of the key. 95
- 30 5. In a combined typewriting and computing machine having numeral-type-keys, a carriage, a totalizer having carry-over trains, and a master-wheel engageable in denominational order with said totalizer by means of said carriage, the combination of a set of key-operated indexing cams for driving said master-wheel, each cam formed to impart an excessive throw to the master-wheel to secure a complete carry-over, and means to disconnect the master-wheel from the cam at the conclusion of the printing stroke of the key, the excessive throw taking place at a point before the key has concluded its printing stroke, and the cam being shaped to cause the master-wheel to recoil from its overthrown position to correct position before the disconnection of the master-wheel at the conclusion of the printing stroke of the key. 100
- 35 6. In a machine of the character described having numeral-keys, a set of totalizer-wheels having carry-over trains, a master-wheel, and a carriage advancing at the operation of said keys, to cause the master-wheel to engage with successive totalizer-wheel denominations; mechanism whereby, at the operation of any key, the latter is connected to rotate the master-wheel according to the key-value and to then disconnect the master-wheel, said mechanism being arranged to drive and overthrow the master-wheel in excess of said value to insure complete 110 operation of the carry-over trains, and to then retract the master-wheel to the correct position for said value before the key stroke in initial direction is completed and before disconnection of the master-wheel. 115
- 40 7. In a machine of the character described having numeral-keys, a set of totalizer-wheels having carry-over trains, a master-wheel, and a carriage advancing at the operation of said keys, to cause the master-wheel to engage with successive totalizer-wheel denominations; mechanism whereby, at the operation of any key, the latter is connected to rotate the master-wheel according to the key-value and to then disconnect the master-wheel, said mechanism being arranged to drive and overthrow the master-wheel in excess of said value to insure complete 120 operation of the carry-over trains, and to then retract the master-wheel to the correct position for said value before the key stroke in initial direction is completed and before disconnection of the master-wheel. 120
